UNITED STATES PATENT OFFICE

FREDERICK W. ROETTGES, OF NEW YORK, N. Y., ASSIGNOR TO LIGHTING APPLIANCE COMPANY, INC., OF NEW YORK, N. Y.

DESIGN FOR A LIGHTING FIXTURE BRACKET OR ARTICLE OF SIMILAR NATURE

Application filed August 8, 1930. Serial No. 36,610. Term of patent 3½ years.

To all whom it may concern:

Be it known that I, FREDERICK W. ROETTGES, a citizen of Germany, residing in New York, in the county of Kings and State of New York, have invented a new, original, and ornamental Design for a Lighting Fixture Bracket or Article of Similar Nature, of which the following is a specification, reference being had to the accompanying drawings, forming a part thereof.

Figure 1 is a front elevational view of a

lighting fixture bracket showing my new design.

Fig. 2 is a side view thereof.

Fig. 3 is a diagrammatic plan view for the purpose of indicating contour.

I claim:

The ornamental design for a lighting fixture bracket, or article of similar nature, as shown.

In testimony whereof I affix my signature.

FREDERICK W. ROETTGES.
